CLAIM

The ornamental design for a charging case, as shown and described.

DESCRIPTION

FIG. 1 is a front perspective view of a charging case showing my new design, shown in an environment of use; FIG. 2 is another front perspective view of the charging case of FIG. 1.

FIG. 3 is a rear perspective view of the charging case of FIG. 1.

FIG. 4 is a rear elevation view of the charging case of FIG. 1.

FIG. 5 is a front elevation view of FIG. 1, shown with environmental structure removed.

FIG. 6 is a front elevation view of FIG. 1.

FIG. 7 is a top elevation view of the charging case of FIG. 1.

FIG. 8 is a bottom elevation view of the charging case of FIG. 1.

FIG. 9 is a right elevation view of the charging case of FIG. 1; and,

FIG. 10 is a left elevation view of the charging case of FIG. 1.

The broken lines in the drawings illustrate environmental subject matter or portions of the charging case which form no part of the claimed design.
